CLAIM

The ornamental design for a control device for endoscope, as shown and described.

DESCRIPTION

FIG. 1 is a top, front and right side perspective view of a control device for endoscope showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an enlarged perspective view of a portion defined by an arrow A and an arrow B of FIG. 2, and an arrow C of FIG. 6, and a display section is in a light emitting state;

FIG. 9 is an enlarged front elevational view of a portion defined by an arrow A and an arrow B of FIG. 2, and a display section is in a light emitting state;

FIG. 10 is an enlarged perspective view of a portion defined by an arrow A and an arrow B of FIG. 2, and an arrow C of FIG. 6, and a display section is in a light-off state;

FIG. 11 is an enlarged front elevational view of a portion defined by an arrow A and an arrow B of FIG. 2, and a display section is in a light-off state; and,

FIG. 12 is a top, front and right side perspective view of an endoscope system including the control device, the endoscope, a monitor display and connection cables.

The broken lines showing the portions of the control device in all views are for illustrative purposes only and form no part of the claimed design.

The broken lines showing the portions in FIG. 12 are for illustrative purposes only and form no part of the claimed design.

(Continued)

The two-dot chain lines in FIGS. 8-11 represent the boundary lines of the partially enlarged range and form no part of the claimed design.
